UNITED STATES PATENT OFFICE.

CHARLES WINDBIEL AND JAMES FIRTH, OF AMSTERDAM, NEW YORK.

PRESSURE-REGULATOR FOR HYDROSTATIC PRESSES.

SPECIFICATION forming part of Letters Patent No. 259,350, dated June 13, 1882.

Application filed February 23, 1882. (No model.)

To all whom it may concern:

Be it known that we, CHARLES WINDBIEL and JAMES FIRTH, both of Amsterdam, in the county of Montgomery and State of New York, have invented certain new and useful Improvements in Pressure-Regulators for Hydrostatic Presses, of which the following is a specification.

Our invention relates to an automatic device for regulating the pressure in hydrostatic presses by controlling the action of the supply-pumps for such presses; and the object of our improvement is to provide a device by which the supply-pumps will be automatically put in motion whenever, by reason of leakage or any other cause, the pressure in the hydrostatic press or presses becomes reduced below the required standard. This object we attain by means of the mechanism illustrated in the accompanying drawings, which form part of this specification, and in which—

Figure 1 is a side elevation of the supply-pumps and regulating mechanism, a portion of the frame for the pumps being broken away to expose the underlying parts; Fig. 2, a plan view of the same, and Fig. 3 a front elevation of the auxiliary cylinder and its attached parts composing the pressure-regulator.

As illustrated in the drawings, A indicates a double-acting supply-pump for forcing water or other liquids into a hydrostatic press or presses for the purpose of producing the required degree of pressure in said press. Said pump is provided with the induction-pipes a, leading into the supply-tank B.

C is the driving-shaft, to which the pulley e is secured; D, a slack driving-belt running from the pulley c to the pulley E, which revolves freely on the shaft F. A pinion, e, is attached to the pulley E in such manner that the said pulley and pinion will revolve as one piece on the shaft F, and the said pinion gears into the wheel G, secured to the shaft H, which carries the pinions h, that gear into the wheels f, secured to the shaft F, for the purpose of imparting a rotatory motion to the latter.

J is an eccentric secured to the shaft F, and provided with a forked connecting-rod, j, which is jointed to the yoke K, which carries the plungers a' for the pump. A reciprocating

motion is imparted to the plungers a' in the following manner: The shaft C is rotated at any required rate of speed for producing the proper number of strokes of the pump-plungers a'. Then, when the belt D is drawn tight in the manner hereinafter described, the pulley E and pinion e will be rotated to set in motion the wheel G and shaft H, whose pinions h, through the wheels f, cause the shaft F to revolve, and thus impart the necessary motion to the eccentric J to reciprocate the pump-plungers a'.

The pump A and its operating mechanism, as above described, are well known, and do not constitute any part of our invention, and we wish to have it distinctly understood that any other pump-operating mechanism may be substituted therefor when preferred.

Our pressure-regulating device consists of an auxiliary cylinder, L, adapted to receive a water-tight working plunger, l, to which a weight, M, is attached by means of the cross-head l' and side rods, l'', or in any other suitable manner, so that the said weight will lie either above or below the cylinder L. A yoke, N, is secured to the side rods, l'', or other part of the device that partakes of the motion of the plunger l. Said yoke is provided with an opening, n, through which passes an arm, O, pivoted at o, and provided at its swinging end with a tightener-pulley, P, which is adapted to bear against the driving-belt D to produce the required degree of adhesion of the said belt to the pulleys e and E. The delivery-pipe Q from the pump A connects with a cross-pipe, R, one limb of which is attached to the cylinder L to force the water into said cylinder beneath the plunger l, and the other limb of the pipe R is connected to the "way-block" S, from which lead the feed-pipes s to the hydrostatic presses, and each of said feed-pipes is provided with the usual stop-valves, s', for shutting off the flow of water through the said pipes, or either of them, when it is required to throw one or more of the presses out of operation.

The operation of our pressure-regulator is as follows: The plunger l is loaded with any weight, M, that is sufficient to resist the pressure exerted by the liquid against the lower end of said plunger to move it (the plunger) 100

upward and to overcome such lifting pressure until the prescribed maximum pressure is obtained. When the pump A is started it forces the liquid through the pipes Q and R into the cylinder L and through the way-block S into the hydrostatic press or presses. Now, it is obvious that under such conditions an equal pressure per square inch will be obtained at the same moment in all the presses, in all the pipes leading from the pump, and against the under side of the plunger l; but the latter remains stationary, and permits the tightener-pulley P to bear against the belt D to keep the pump A in operation until the maximum pressure is attained, and then the plunger l will be forced upward, and thereby the yoke N will raise the arm O and remove the tightener-pulley P from the belt D, as indicated by the dotted lines in Fig. 1, so as to permit the driving-shaft C to rotate without imparting any motion to the pump-operating mechanism. Whenever the fluid-pressure from any reason recedes below the maximum point, the weight M will force the plunger l to move downward, so that the tightener-pulley P will again bear against the belt D to set in motion the pump A to restore the required pressure.

When preferred, a spring may be substituted

for the weight M on the plunger l of our regulator.

30

We claim as our invention—

1. A pressure - regulator for hydrostatic presses, composed of an auxiliary cylinder containing a movable plunger controlled by means of a weight or spring, in combination with and operating the connecting and disconnecting devices of the pump-driving mechanism, as herein set forth, the said auxiliary cylinder being connected to the feed-pipes for the presses in such manner that the same pressure will be found in the said cylinder and feed-pipes for the purpose of maintaining the pressure in a hydrostatic press or presses at the maximum point of pressure, as herein specified.

35

2. The auxiliary cylinder L, provided with a weight or spring governed plunger, l, adapted to automatically connect and disconnect the operating mechanism of the supply-pump for hydrostatic presses, in the manner and for the purpose herein specified.
